UNITED STATES PATENT OFFICE

NICOLAS MARTINEZ, OF LERIDA, SPAIN

BOOT CLEANING AND POLISHING MACHINE

Application filed June 6, 1923, Serial No. 643,713, and in Spain June 12, 1922.

This invention relates to a boot cleaning polishing machine and consists in the provision of a revolving wheel mounted on a vertical shaft and carrying hingedly arranged [5] brushes for the treatment of different parts of boots supported on a grating which is rigidly held above the wheel, means being provided for applying the brushes to the boots by the centrifugal action of weight-balanced levers.

Fig. 1 of the accompanying drawings represents a vertical section of the apparatus, the brushes being omitted for the sake of clearness, and

Fig. 2, a plan of the same, partly in section, and also without the brushes.

Fig. 3 is a plan showing the preferred construction of the brush wheel, and

Fig. 4, a plan of the boot support.

Fig. 5 is a transverse section showing the operation of the brushes, and

Fig. 6, a partial plan of the wheel and of the operating levers.

Fig. 7 is a composite view illustrating the 25 means for supporting the brushes which operate on the upper part of the shoe.

Fig. 8 is a composite view illustrating the several parts of the brush which operates on the rear and heel portion of the shoe.

Fig. 9 is a composite view illustrating one 30 of the cloth brushes adapted to polish the instep and toe of the shoe.

Fig. 10 is a composite view showing a type 35 of frame on which the brush of Fig. 9 may be mounted.

The machine is preferably mounted in a cavity 8 surrounded by a circular wall 6 of masonry, the top of the wall being flush with the floor of a shop or with a pavement or the 40 like. Steps 9 lead down from the floor into the cavity which is large enough to provide accommodation for the machine operator. The machine is composed of a vertical steel shaft 10 which is supported by balls in a step-bearing arranged at the bottom of the cavity 8. The upper end of the shaft is also supported by a ball-bearing which may be fixed to some part of the shop fitting, but which is 45 preferably held in a frame work 4 composed of six radial arms whose outer ends are em-

bedded in and supported by the masonry 3 as shown in Fig. 1. Suspended by means of screw-bolts from the arms 6 is a ring-shaped grating 5 which is fitted with a plurality of foot pads 11 made of iron or hard wood. The 55 ring 5 is arranged so that the foot pads are in a convenient position for use by occupants of seats 7 mounted on top of the masonry 6. In the construction shown, there is accommodation for five persons whose boots will all 60 be cleaned by a single operation of the machine. The seats are supported by screw spindles so that they can be adjusted to different levels in the usual manner.

Connected to the shaft 10 underneath the 65 foot support 5 is a brush wheel 1 which may be composed of a suitably stayed disc but which is preferably, for the sake of lightness and cheapness, composed of a skeleton comprising radial arms of channel iron which are 70 distanced by transverse, light iron strips, as shown in Fig. 3. In the present instance there are ten radial arms, and each arm carries at its extreme end a brush 12 for the treatment of the sides and heel parts of the boots 75 supported on the ring 5. A polygonal drum 2 having ten sides, is supported on and secured to the arms of the wheel 1 so as to rotate within the ring 5. Connected to the upper edge of this drum are ten brushes 13 for the treatment of the toe and instep parts of the boots. The brushes 13 are arranged over the spaces between the wheel arms so as to come into operation alternately with the brushes 12. By this arrangement the friction 80 will be more uniformly distributed over the wheel and a jerkless movement will be obtained. There are also five brushes 14 connected to alternate wheel arms and arranged so as to be applied to the lower sides of the 85 boots. These latter brushes work through apertures in the grating 5.

The brushes are mounted on arms which are hingedly connected to the wheel so that 90 they can be turned into and out of operative position. The arms 12^a of the brushes 12 are fitted with weighted tail pieces 12^b which, while suspended vertically from the hinge, hold the brushes in inoperative position, as shown by dotted lines in Fig. 5. During the 100

movement of the wheel, however, the tail pieces are tilted by centrifugal force so as to apply the brushes to the boots. This is shown by full lines in Fig. 5. The brushes 13 are similarly arranged on the drum 12 by means of right-angled arms 13^a whose tail pieces 13^b are engaged by stirrups formed at the upper end of double-armed levers 13^c pivoted to the wheel. The lower ends of the levers 13^c are connected by rods 15 to weighted arms 16 which are suspended from hinges connected to the wheel. The arms 16 tend to maintain the brushes 13 in the inoperative position shown dotted in Fig. 5, and to turn them into the operative position shown by full lines under the action of centrifugal force when the wheel moves. Springs 17 aid the arms 16 in restoring the brushes 13 to the inoperative position as soon as the machine stops.

20 The brushes 14 may either be controlled in a similar manner or adapted to be set by hand in working position. The counter-weights are adjustable by means of screw-threads for varying the leverage and thereby the effect 25 of the centrifugal force.

According to the services for which they are intended, the brushes are made up of different materials such as bristles, hair or cloth. The construction of the cloth brushes is illustrated in Fig. 9: The working face 19 is a cloth-covered surface carried by a resilient support 20 made of spring steel. The brush is secured by means of the support 20 to the operating arm which is preferably constructed like a frame. Fig. 10 shows such a frame shaped for use on the drum 2.

40 The operation may be divided into five stages, viz, the removal from the boots of dust and mud; the application thereto of a waterproofing or colouring substance; the rubbing of such substance into the leather; the application of a polishing paste; and the rubbing of the latter. For each of these 45 stages a separate brush or brushes are used, the other brushes being maintained in inoperative position. For cleaning the boots there may be one brush made with stiff bristles and one made up of linen or the like. 50 For the application of the waterproofing substance and colouring matter two hair brushes are used, and one bristle brush is used for the rubbing in of the same. The application of the polishing paste is also effected by means 55 of two hair brushes, and the final shine is produced by means of two bristle brushes and two cloth brushes. This arrangement applies to the position 12 as well as to the position 13, all the ten brushes being thus utilized in both cases. In the position 14 it is sufficient to have one brush of suitable character for each stage of operation.

60 The shaft 10 is geared to a horizontal driving shaft 21 which may be operated by means of an electro-motor 22 or the like

through the medium of two belts 23 of which one is crossed so that movement can be imparted to the shaft in either direction. As the machine is very easily operated, however, the shaft 21 may be fitted with a crank handle and rotated by hand. In the case of machine power, a brake disc 3 is fitted on the shaft 10 so that the speed of the latter can be regulated by means of a brake band 24 arranged on said disc, the free end of the band 75 being connected to a lever or treadle 25 whereby the brake is operated.

70 The cleaning brushes are released for operation, and the brush wheel is rotated at a high speed. A few turns in each direction will be sufficient for removing all dust and mud from the boots of the five clients occupying the 80 seats. The cleaning brushes are then fixed in inoperative position, and the brushes for applying the waterproofing or colouring substance are fixed in operative position, whereupon the wheel is rotated a few turns in each direction and at a low speed. These 85 brushes are then restored to and fixed in inoperative position whereupon the rubbing brushes for the third stage of the operation are released and the wheel is rotated a few turns in both directions at high speed. The 90 polishing substance is applied and the final shine is produced in a similar manner, the whole operation of cleaning and polishing being carried out in a very short space of time. During the change of clients, the 95 operator provides the hair brushes with a 100 fresh supply of paste.

The cleaning and rubbing brushes are automatically applied to the boots as soon as the machine is set in rotation, and are automatically withdrawn as soon as the machine stops.

105 When the machine is erected in the open it is advisable to arrange the top bearing for the shaft 10 underneath the wheel 1 so that the entire mechanism will be situated underground. Between the working hours the 110 mouth of the cavity may be suitably covered. Other modifications may be adopted to suit different localities and conditions, and the actual arrangement also depends on whether the structure is of a temporary or permanent 115 nature.

I claim:

1. A boot cleaning apparatus including a mechanism pit open at the top, a plurality of seats for patrons positioned about the upper open edge of the pit, a skeleton framework carried by the upper edge of the pit, a foot support suspended from said skeleton framework in the open central portion of the pit, said foot support being a ring like member 120 provided with openings and having foot rests thereon opposite each patron's seat, a vertical shaft having its lower end journaled in the bottom of the pit and its upper end journaled in the skeleton framework, a brush 125

carrying frame carried by said shaft beneath said foot support, an upstanding drum mounted centrally of the brush support and projecting within and above said ring like foot support, counterbalanced brushes carried by said brush frame and by said drum and adapted to be brought into operative position by centrifugal force when the frame is rotated, and means for rotating said shaft.

2. A boot cleaning apparatus comprising a support having a cavity therein, a plurality of patrons' seats arranged around the upper edge of the cavity, a ring like foot support suspended in the cavity below the surface of said first mentioned support and carried thereby, and a rotatable brush carrying device having a portion projecting upwardly into the ring like foot support, and a plurality of brush devices carried by the portion of said brush carrier projecting into the ring like foot support and also carried by the intermediate and outer edge portions of said brush carrier, and means for rotating said brush carrier.

3. A boot cleaning and polishing machine comprising a vertical rotatory shaft, a circular wall surrounding said shaft, a radial frame work embedded in and supported by the upper part of said wall, the shaft being supported by said frame work, adjustable seats supported on said wall and arranged about the frame work, a ring-shaped foot support suspended from said frame work within the confines of the wall so that it can be used by persons occupying the seats, a brush wheel secured to the shaft underneath the foot support, counterbalanced brushes pivotally connected to said wheel for brushing different parts of boots placed on the foot support when the brush wheel is rotated, and means for rotating the shaft so as to operate the wheel and brushes.

4. A boot cleaning and polishing machine comprising a vertical rotatable shaft, a stationary foot support arranged about said shaft, a brush wheel secured to the shaft under the foot support, brushes connected hingedly to said wheel, counter-weights connected to said brushes so as to hold them normally out of contact with boots placed on the foot support and so as to turn them into contact therewith by centrifugal force when the wheel is rotated, and means for rotating the shaft so as to operate the wheel and brushes.

In testimony whereof I affix my signature.
NICOLAS MARTINEZ.
